SYSTEM FOR AUTOMATICALLY RELEASING CONNECTION BETWEEN CARS IN TRAIN

BACKGROUND OF THE INVENTION

This invention relates to a system for automatically releasing the connection between cars in a train by a combination of electrical and pneumatic controls, and more particularly to a labor-saving system in which an electrical and a pneumatic signal supplied from the locomotive are utilized to automatically release the coupler between cars composing a train.

DESCRIPTION OF THE PRIOR ART

Heretofore, the cooperation of at least three persons, that is, a trainman aboard the locomotive, an operator working on the coupling portion of a car to be disconnected from the next adjacent car, and a watcher who stands outside of a train to send a signal to the trainman and operator, has been required to compose a train. Thus, not only the car releasing or disconnecting operation for composing a train has required many hands and has been time-consuming, but also it has involved much danger. There has therefore been an increasing demand for the automation of such a troublesome and dangerous operation from the viewpoint of safety, economy, labor-saving saving and rationalization of the operation so that any desired car among several or several ten cars connected as a train can be disconnected from the next adjacent car at any desired place in a factory, yard or the like by mere manipulation of the trainman aboard the locomotive.

SUMMARY OF THE INVENTION

It is therefore a primary object of the present invention to provide a system for automatically carrying out such a troublesome and dangerous car disconnecting operation so that simple manipulation by a trainman aboard the locomotive can easily release the coupler between any desired car and the next adjacent car in a train.

According to the present invention, the following advantages can be obtained:

1. Any desired car in a train can be disconnected from the next adjacent car at any desired place by simple manipulation by a trainman aboard the locomotive. Heretofore, the car disconnecting operation has been carried out by the cooperation of the trainman, an operator working on the coupling portion of the car to be disconnected from the next adjacent car, and a watcher sending a signal to the trainman and operator, and thus it has involved danger and required extra hands.
2. A single air conduit extending through the train and a single positive feeder wire extending through the train are only necessary for effecting the automatic disconnection of the specific car irrespective of the number of cars composing the train. (In the present invention, the rails serve as a negative feeder).
3. The car can be disconnected from the preceding or succeeding car as required.
4. In connection with the sorting operation on a yard, the system of the present invention may be operated in combination with other equipment to further promote the degree of automation.

5. The car disconnecting operation can be positively carried out and the period of time required for operation can be reduced due to the fact that air under pressure is utilized to produce the force for the disconnection under control of an electrical signal.

The above and other objects, features and advantages of the present invention will be readily apparent from the following detailed description of a preferred embodiment thereof taken in conjunction with the accompanying drawings.

BRIEF DESCRIPTION OF THE DRAWINGS

FIG. 1 is a schematic diagram of a system for automatically releasing the connection between cars in a train embodying the present invention.

FIG. 2 is a schematic diagram of parts of the system in a locomotive and a first car connected to the locomotive, showing the state of supplying air under pressure from the locomotive to succeeding cars including the first car.

FIG. 3 is a schematic diagram of parts of the system in a second car, showing the state of relaying air under pressure supplied from the locomotive through the first car for supplying the air under pressure to succeeding cars.

DESCRIPTION OF THE PREFERRED EMBODIMENT

Referring to FIG. 1, a train is composed of a locomotive A and several or several ten cars among which only two cars B₁ and B₂ connected successively are shown herein. The locomotive A and the cars B₁ and B₂ are connected by means of automatic couplers. The automatic couplers are of the type in which a pair of opposite coupler elements are brought into engagement with each other for establishing a firm coupling thereby attaining the connection and are released for disconnection by the operation of an actuating lever. The automatic coupler of this type is well known in the art and any detailed description as to it is unnecessary.

According to the present invention, the locomotive A is provided with a counter controller AA for instructing the disconnecting operation, a solenoid-operated valve 1 operative in response to an electrical signal applied from the counter controller AA, a change-over valve 2 operative in response to the operation of the solenoid-operated valve 1 to supply air under pressure to and exhaust air under pressure from the succeeding cars B₁ and B₂, a pressure reducing valve 3 provided with a by-pass valve which does not reduce the air pressure during the supply of air to the cars B₁ and B₂ but reduces the air pressure during the exhaust of air from the cars B₁ and B₂, receivers Aa and Ab for receiving electrical signals transmitted from the cars B₁ and B₂ by way of wire, and a transmitter Ac for transmitting an electrical signal to the cars B₁ and B₂ by way of wire.

60 The car B₁ is provided with a double check valve 4 which is operable in both the forward and reverse directions of the car, check valves 5, 6, 14 and 15, a change-over valve 7 which, when actuated, relays air under pressure to the succeeding car B₂, a solenoid-operated valve 10 for supplying air under pressure to and exhausting it from unlocking cylinders Y₁ and Y₂ which act to release the automatic coupler, a change-

over valve 11 for establishing a path of air under pressure to either the unlocking cylinder Y_1 or Y_2 which is nearer to the locomotive A depending on the direction of connection of the car, an air reservoir 9 for reserving air under pressure for supplying it to the unlocking cylinders Y_1 and Y_2 , a check valve 8 for preventing escapement of air under pressure from the air reservoir 9 during the exhaust of air from the unlocking cylinder Y_1 or Y_2 nearer to the locomotive A, switches 12 and 13 for sensing the completion of the operation of the respective unlocking cylinders Y_1 and Y_2 , an air pressure responsive switch 16 which is turned on and off depending on the change-over operation of the change-over switch 7, a transmitter B_1a for transmitting to the locomotive A by way of wire a signal representative of the on-state of the air pressure responsive switch 16, a transmitter B_1b connected to the switches 12 and 13 for transmitting to the locomotive A by way of wire a signal representative of the completion of the operation of the unlocking cylinder Y_1 or Y_2 sensed by the switch 12 or 13, and a receiver B_1c for receiving an electrical signal from the locomotive A by way of wire thereby energizing the solenoid-operated valve 10.

Similarly, the car B_2 is provided with a double check valve 4', check valves 5', 6', 14' and 15', a change-over valve 7', a solenoid-operated valve 10', unlocking cylinders Y_1' and Y_2' , a change-over valve 11', an air reservoir 9', a check valve 8', switches 12' and 13', an air pressure responsive switch 16', transmitters B_2a and B_2b , and a receiver B_2c .

The present invention is featured by the fact that the actuating lever for the automatic coupler is operated by electrically and pneumatically controlled means linked by a single air conduit and a single electric wire.

The operation of the system according to the present invention will be described with regard to the case in which the automatic coupler between the first and second cars B_1 and B_2 is released. In releasing the automatic coupler between the first and second cars B_1 and B_2 , the counter controller AA mounted in the locomotive A is set at "2" meaning the second car B_2 . Upon setting the counter controller AA at such a position, the switch in the counter controller AA is turned on to energize the solenoid-operated valve 1 so that air under pressure supplied from a source flows through a conduit a into a conduit b to actuate the change-over valve 2 as shown in FIG. 2. Since the change-over valve 2 takes the position shown in FIG. 2, air under pressure from the supply source flows through a conduit c into a conduit d , thence through the by-pass valve section of the pressure reducing valve 3 into a conduit e to be supplied to a conduit a_1 in the succeeding car B_1 . In the car B_1 , air under pressure supplied to the conduit a_1 passes through the check valve 14 and a conduit j_1 , thence through the double check valve 4 and conduits b_1 and l_1 into the pilot section of the change-over valve 7 to charge the pilot section with air under pressure. The air cannot flow from the conduit a_1 into the conduit containing the check valve 5, and air under pressure acts upon the pilot section of the change-over valve 11 so that it takes a position in which air is supplied to the unlocking cylinder Y_1 . Air under pressure in the conduit l_1 flows also through the check valve 8 to charge the air reservoir 9, and at the same time, controls the air pressure responsive switch 16. When the air pressure in the

conduit l_1 exceeds x_1 kg/cm², for example, 3 kg/cm², the air pressure responsive switch 16 takes its "on" position and the transmitter B_1a transmits an electrical signal at a frequency of α cycles per second, for example, 200 cycles per second by way of wire. This signal is received by the receiver Aa mounted in the locomotive A, and the counter controller AA confirms the reception of the signal and identifies whether the signal is transmitted from the designated car or not. Since the signal is sent from the car which is not designated, the counter controller AA merely counts and stores "1." In the meantime, the pressure of air in the conduit l_1 is successively raised due to continuous supply of air from the locomotive A, and when it exceeds x_2 kg/cm², for example, 4 kg/cm², the air pressure responsive switch 16 takes its "off" position. As the air pressure in the conduit l_1 is raised further until it exceeds x_3 kg/cm², for example, 5 kg/cm², the change-over valve 7 is changed over to the position shown in FIG. 2 with the result that air under pressure in the conduit l_1 flows through a conduit c_1 to reach the check valves 5 and 6. The flow of air under pressure reaching the check valve 5 cannot pass therethrough because the pressure in the conduit a_1 is higher than or equal to the pressure in the conduit c_1 . The flow of air under pressure reaching the check valve 6 through the conduit c_1 passes through the valve 6 and a conduit h_1 to be supplied to the succeeding car B_2 .

The flow of air under pressure in the car B_2 is similar to that in the car B_1 . Air under pressure supplied from the locomotive A passes through the car B_1 to flow into a conduit l_2 in the car B_2 . When the air pressure in the conduit l_2 exceeds x' kg/cm², for example, 3 kg/cm², the air pressure responsive switch 16' takes its "on" position so that the transmitter B_2a transmits an electrical signal at a frequency of α cycles per second, for example, 200 cycles per second by way of wire. This signal is received by the receiver Aa mounted in the locomotive A and the receiver Aa instructs the counter controller AA that the signal at α cycles per second is transmitted from the car. The counter controller AA confirms the reception of the signal and identifies whether the signal is transmitted from the designated car. Due to the fact that the signal is sent from the designated car B_2 , the counter controller AA deenergizes the solenoid-operated valve 1 to interrupt the supply of air from the locomotive A and to exhaust air from the cars. (The counter controller AA has stored "1" by receiving the signal from the car B_1 and now reads "2" upon receiving the signal from the car B_2 . It will be recalled that the counter controller AA is set at "2." Thus, the reception of the signal from the car B_2 satisfies the above setting). Simultaneously with the deenergization of the solenoid-operated valve 1, the transmitter Ac transmits to the receivers B_1c and B_2c in the respective cars B_1 and B_2 an electrical signal at a frequency of β cycles per second, for example, 400 cycles per second by way of wire. Since the air pressure responsive switch 16' in the car B_2 is solely in the "on" position, the receiver B_2c in the car B_2 can solely receive the signal at β cycles per second transmitted from the transmitter Ac by way of wire. As a result, the solenoid-operated valve 10' is energized to connect a conduit d_2 with a conduit l_2 so that air under pressure in the air reservoir 9' is supplied through the change-over

valve 11' (which takes now the position shown in FIG. 1) and through a conduit f_2 into the unlocking cylinder Y_1' to actuate the same thereby releasing the automatic coupler between the cars B_1 and B_2 . Immediately before the unlocking operation is completed, the switch 12' is actuated so that the transmitter B_2b transmits an electrical signal at a frequency of α cycles per second, for example, 600 cycles per second by way of wire to indicate the fact that the unlocking cylinder Y_1' has been operated. This signal is received by the receiver Ab in the locomotive A and the counter controller AA confirms the unlocking of the automatic coupler, thereby completing all the operation for the unlocking of the automatic coupler.

The operating speed of the system in response to the second and subsequent unlocking instructions is faster than that in response to the first unlocking instructions because air at pressure of x_3 kg/cm² remains in the conduit portion ranging from the check valve 8 through the air reservoir 9 to a conduit d_1 , and air at pressure of x_0 kg/cm², which is lower than the setting x_2 kg/cm² of the air pressure responsive switch 16 remains in the air exhausting line leading to the pressure reducing valve 3 provided with the by-pass valve.

While a preferred embodiment of the present invention has been described in detail in the above by way of example, the present invention is in no way limited to such a specific embodiment and many changes and modifications may be made therein without departing from the spirit of the present invention.

We claim:

1. A system for automatically releasing the connection between cars in a train by a combination of electrical and pneumatic controls comprising means for supplying air under pressure from the locomotive to pneumatically operated means mounted in each car for releasing the connection between any desired car and the next adjacent car by means of an unlocking cylinder operated by air pressure, and electrical means mounted in the locomotive and each car for designating the specific car to be disconnected and instructing the pneumatically operated means in the designated specific car to carry out the disconnecting operation, characterized in that said pneumatically operated means comprises a first change-over valve for controlling the passage of the air to the next car and having a pilot section to which the air from said locomotive is introduced, a second change-over valve having a pilot section to which the air from said locomotive is introduced, and an air pressure responsive switch supplied with the air from said locomotive, said pressure responsive switch being in the "off" state when the air pressure is below a first value and being capable of being changed from the "off" state to the "on" state

when the air pressure exceeds said first value and then to the "off" state when said pressure further increases over a second value, said first change-over valve being actuated to permit the passage of air to the next car in the train when said air pressure acting upon said pilot section exceeds said second value, said electrical means comprising a first transmitter mounted on said car for transmitting a first signal of a first predetermined frequency when said air pressure switch is in the "on" state in response to the application of the air pressure between the first and second values, a first receiver mounted on said locomotive for receiving said first signal from said first transmitter, a second transmitter mounted on said locomotive for transmitting a second signal of a second frequency when the car transmitting said first signal is a car to be disconnected, a third receiver mounted on said car for receiving said second signal and actuating a third change-over valve arranged upstream of said second change-over valve so that the air from said locomotive is passed through said third and second change-over valves to actuate an unlocking cylinder of the car to be disconnected.

2. A system according to claim 1 in which each car has an unlocking cylinder for the coupler at one end of the car and an unlocking cylinder for the coupler at the other end of the car, the said second change-over valve being operated by air from the locomotive to direct air under pressure to the unlocking cylinder for the coupler at the end of the car toward the locomotive.

3. A system according to claim 1 in which each car has an air reservoir for supplying actuating air for the unlocking cylinders, said air reservoir being charged by air from the locomotive.

4. A system according to claim 1 having electric circuit means for transmitting a signal to the locomotive after the unlocking cylinder has been actuated.

5. A system according to claim 1 wherein the second signal from the locomotive interrupts the supply of air from the locomotive to the cars.

6. A system according to claim 1 wherein the locomotive is provided with a counter controller which can be set at a count designating a car whose coupler is to be released, each said first signal received by said receiver on said locomotive advancing said counter controller one count, said counter controller transmitting said second signal when the counter controller reaches the count designating the car whose coupler is to be released.

7. A system according to claim 1 wherein the said second signal is transmitted to all of the cars of the train and actuates the third change-over valve of only the designated car whose air pressure switch is then in the "on" state.
